(57) **CLAIM**

The ornamental design for a demagnetization apparatus, as shown and described.

DESCRIPTION

1. Demagnetization apparatus

1.1 is a front view;

1.2 is a side view;

1.3 is a front perspective view;

1.4 is a rear perspective view; and

1.5 is a bottom view.

In the drawings, the broken lines are for the purpose of illustrating portions of the demagnetization apparatus that forms no part of the claimed design.
